UNITED STATES PATENT OFFICE.

JOHN J. HEYS, OF LYNN, MASSACHUSETTS, ASSIGNOR TO UNITED SHOE MACHINERY COMPANY, OF PATERSON, NEW JERSEY, A CORPORATION OF NEW JERSEY.

SOLE-CUTTING DIE.

1,124,739.

Specification of Letters Patent.

Patented Jan. 12, 1915.

Application filed March 21, 1912. Serial No. 685,293.

To all whom it may concern:

Be it known that I, JOHN J. HEYS, a citizen of the United States, residing at Lynn, in the county of Essex and State of Massachusetts, have invented certain Improvements in Sole-Cutting Dies, of which the following description, in connection with the accompanying drawings, is a specification, like reference characters on the drawings indicating like parts in the several figures.

This invention relates to improvements in dies for cutting sheet material and more particularly to dies for cutting out the soles of boots and shoes from sole leather. Dies intended for this use frequently weigh as much as eight or ten pounds and the continuous lifting and manipulation of such dies at practically arm's length and breast high, which is necessary in cutting soles in a beam press, is extremely fatiguing work for the workman or cutter. The manipulation of dies of this type as heretofore constructed is rendered more arduous by reason of the fact that the cutter has been obliged to grip or squeeze the sides of the die in order to lift it and this gripping of the die each time it is lifted calls for a further expenditure of energy.

Various attempts have been made heretofore to facilitate the handling of sole dies. For example, it has been proposed to secure a narrow strap or band about the upper edge of the die or to corrugate its outer surface. None of these expedients, however, has been successful and none has rendered unnecessary gripping the die quite firmly with the fingers whenever it is to be lifted.

It is the purpose of the present invention to provide a sole die with lifting devices having portions arranged to overlie the fingers of the cutter so that in lifting the die its weight will be carried entirely by the engagement of the lifting devices with the upper surface of the hands and fingers or in other words, the die will be suspended by the engagement of the cutter's fingers with a substantially horizontal surface rather than by the frictional engagement of his fingers with the vertical sides of the die or with the sharp edge of a strap as heretofore used or the curved and inclined surface of a corrugation.

As herein shown the lifting devices are

substantially crescent shaped and have a laterally extending flange located with its plane upper surface below the pressure receiving edge of the die, and beneath the flange, a concave portion with a curved surface shaped to fit the curvature of the inner and upper surfaces of the thumb and forefinger. The concave portion has a maximum depth and thickness below the center of the flange and tapers upwardly and inwardly toward either end thus conforming to the natural shape of the hand engaging the die, and rendering the die comfortable to the hand. An important advantage of these novel lifting devices is that they cause the hands lifting the die to slide inwardly into engagement with the walls of the die and to stay there without effort on the part of the cutter. It is not necessary, therefore, for the cutter to expend any strength in pressing his hands against the opposite ends of the die and he has only to lift the die in moving it from one position to another on the hide. This is an important consideration on account of the great number of times a heavy sole cutting die must be lifted in a day's work. In addition to these advantages the concave portion facilitates securing the lifting device to the die. An advantage of disposing the upper surface of the lifting devices below the plane of the pressure receiving edge of the die is that there is no possibility of the beam of the press striking and breaking the device as would otherwise be likely to happen if the die should be tilted by a wrinkle in the hide.

The lifting devices herein disclosed are of great assistance in manipulating the die but they are further useful as safety appliances for preventing the fingers of the cutter from slipping over the upper edge of the die where they would be crushed by the beam of the press, an accident which has been all too common heretofore.

The nature of the present invention will be best understood and its advantages appreciated from the following description of a preferred embodiment thereof, selected for purposes of illustration, and shown in the accompanying drawings, in which—

Figure 1 is a view in perspective of the die as held in the cutter's hands. Fig. 2 is a sectional view on the line 2—2 of Fig. 1. Fig. 3 is a view in perspective of one of the lifting devices separated from the die.

The die itself comprises an endless frame of steel shaped to correspond with the soles it is desired to produce and having a lower sharpened cutting edge 10 and a parallel flat pressure receiving edge 12. The inner wall of the die extends vertically from the cutting edge for a short distance and is then offset outwardly at 14 to give clearance for the cut out soles so that they may pass freely upwardly within the body of the die. The outer surface of the die is beveled at its lower edge to form the cutting edge and above the bevel extends substantially vertically to the pressure receiving edge 12.

15 The lifting devices are attached at the toe and heel ends of the die by riveting, soldering or other suitable means and, as shown in Figs. 2 and 3, each comprises a crescent-shaped member having a curved flange 16 with a plane upper surface and a lower concave portion 18 beneath the flange. In such construction the maximum width of the flange will be at the end of the die and its width will be reduced toward either end of 20 the flange. The inner surface 20 of each member is curved to fit the curved end of the die to which they are to be secured. The lower portion 18 of each lifting device has a maximum width and depth below the 25 center of the flange and tapers upwardly and inwardly toward both ends of the flange. The surface of this portion is concaved to fit the curvature of the fingers of a hand grasping the die. The outer edge of 30 the flange 16 is shaped to present a smooth unbroken contour and extends from the wall of the die at one side around to the wall of the die on the other side, approaching the walls on either side at an acute angle. This 35 construction is advantageous because a flange so shaped offers no salient angle or corner which will be likely to damage either the hands of the workman or the leather.

The lifting devices are secured to the ends 40 of the die in such position that the upper face of the flange 16 is disposed somewhat below the upper edge of the die, and so located that they are safely out of range of the beam of the press even though the die 45 should become slightly tilted upon the hide.

In manipulating the die of my invention the cutter will grasp the ends of the die in the natural and customary manner and it will be found that the surfaces of the lifting devices conform to the shape of the upper and inner surfaces of the thumb and fingers, and that by overlying a portion of the cutter's hand all necessity is eliminated of calling upon the muscles of the fingers 55 in the effort to lift the die by frictional engagement with its vertical walls.

It will be apparent that, by reason of the characteristic shape of the lifting devices, the beneficial results above set forth are 60 secured without materially increasing the

weight of the die. While other forms of lifting devices could be employed within the scope of the present invention, it is believed that the form herein shown is particularly well adapted to the requirements of the case 70 in that the flange may be made of any desired configuration to afford extended lifting surface without appreciably increasing the weight in the die, while the lower concave portion is convenient in securing the 75 lifting device in place and also contributes to the comfort of the cutter by nicely fitting the natural contour of the hand.

Having thus described my invention, what I claim as new and desire to secure by Letters Patent of the United States is:

1. A sole die having at each end a lifting device comprising a curved flange with a concave portion projecting downwardly from the flange, the lower surface of the 85 concave portion merging into the sides of the die in a line disposed in a plane oblique with respect to the plane of the cutting edge of the die.

2. A sole die having at each end a lifting device comprising a crescent-shaped flange with a concave portion projecting downwardly and tapering at each end toward the outer wall of the die, the lifting devices being secured to the die with the 95 upper surface of the flange below the pressure receiving edge of the die.

3. A sole die having lifting devices secured to its toe and heel ends, said devices having an upper laterally extending portion 100 adapted to overlie part of the cutter's hands and extending sufficiently to prevent upward slipping of the hands as the die is loosely held and having a lower portion shaped to fit the inner surfaces of the thumb 105 and forefinger and inclined obliquely upwardly toward the middle portion of the die.

4. A sole die having a cutting edge, a pressure receiving edge, and lifting devices 110 secured to the ends of the die, each device including engaging surfaces curved transversely of the die and inclined longitudinally of the die upwardly toward the center thereof for causing the hands lifting the die 115 to slip toward each other and into engagement with the end walls of the die.

5. A sole die having a lifting device at one end comprising a crescent-shaped flange and a curved lower portion having a maximum depth at the center of the flange and tapering upwardly toward either end of the flange.

6. A sole die having a cutting edge, a flat pressure receiving edge, and lifting devices 125 secured to the toe and heel ends of the die, each device having a thin flange disposed with its upper surface below the plane of the pressure receiving edge of the die and extending outwardly sufficiently to prevent 130

upward slipping of the hands as the die is loosely held, the inner edge of the flange being curved to fit the die, its outer edge having a different curvature, being of a smooth unbroken contour throughout and so shaped as to give the flange a maximum width substantially opposite to the ends of the die and curving inwardly toward the sides of the die at each end so that the inner ends of the flange are reduced to a minimum width.

7. A sole cutting die having a pressure receiving edge, a lifting device secured to the heel end of the die with its upper surface below the plane of the pressure receiv-

ing edge of the die, and another lifting device secured to the toe end of the die and similarly disposed, each lifting device being substantially crescent-shaped and so constructed and arranged with relation to the 20 contour of its respective end of the die that its outer edge approaches the walls of the die on either side at an acute angle.

In testimony whereof I have signed my name to this specification in the presence of 25 two subscribing witnesses.

JOHN J. HEYS.
